United States Patent Office

Des. 207,757
Patented May 23, 1967

207,757

ELECTRIC RANGE

James Leonard Raulston, 800 Holly Ave., and Stephen L. Rogers, Jr., 400 Magnolia Ave., both of South Pittsburg, Tenn. 37380

Filed July 29, 1966, Ser. No. 3,272

Term of patent 14 years

(Cl. D81—4)

Fig. 3

Fig. 4

Fig. 5

Fig. 8

Fig. 9

FIG. 1 is a front perspective illustrating the top and one side of the design;

FIG. 2, a back elevation of the electric range;

FIG. 3, a top plan view;

FIG. 4, a side elevational view illustrating the opposite side from the one shown in FIG. 1;

FIG. 5, a fragmentary perspective with one of the doors open and illustrating the control panel;

FIG. 6, a front elevational perspective illustrating a modification of the design shown in FIG. 1;

FIG. 7, a side elevation illustrating the opposite end seen in FIG. 6;

FIG. 8, a top plan view of a modified design of the range; and

FIG. 9, a back elevation of the range illustrated in FIG. 6.

We claim:

The ornamental design for an electric range, as shown and described.
